VAULT VENTILATOR

Kango Hinohara, Hiroshima-shi, Japan, assignor to
Kabushiki Kaisha Kumahira Seisakusho, Hiroshima-shi, Japan

Filed Oct. 21, 1966, Ser. No. 4,376

Term of patent 7 years

(Cl. D69—1)

FIG. 1

FIG. 2

FIG. 3

FIG. 4

FIG. 5

FIG. 6

FIG. 7

FIG. 1 is a front elevational view of a vault ventilator showing my new design;

FIG. 2 is an elevational view taken from one side thereof;

FIG. 3 is an elevational view taken from the side opposite that shown in FIG. 2;

FIG. 4 is a rear elevational view thereof;

FIG. 5 is a top plan view thereof;

FIG. 6 is a bottom plan view thereof; and

FIG. 7 is a perspective view thereof.

I claim:

The ornamental design for a vault ventilator, substantially as shown.
